George W. Moore
ATTORNEY.

UNITED STATES PATENT OFFICE.

CHARLES BAIA, OF JERSEY CITY, NEW JERSEY.

LOCKING DEVICE FOR PURSES AND POCKET-BOOKS.

1,360,613.

Specification of Letters Patent. Patented Nov. 30, 1920.

Application filed March 6, 1920. Serial No. 363,819.

To all whom it may concern:

Be it known that I, CHARLES BAIA, a citizen of the United States, and a resident of Jersey City, Hudson county, State of New Jersey, have invented certain new and useful Improvements in Locking Devices for Purses and Pocket-Books, of which the following is a specification.

My invention relates to improvements in locks for purses, bags, pocket-books and the like and has for its object the construction of a simple device of this kind which may be readily manipulated and remain in closed position unless its operating mechanism is positively moved by hand to enable the unlocking of the purse, bag, etc.

In the accompanying drawings, Figure 1 is a longitudinal vertical section of my construction showing the locking member and the keeper member separated.

Fig. 2 is a like view with these parts in engagement with one another.

Fig. 3 is a detail view taken in the direction of the arrow 3 shown in Fig. 2.

Fig. 4 is a like view taken on line 4—4 of Fig. 2.

Fig. 5 is a sectional view taken on line 5—5 of Fig. 1.

Fig. 6 is a section taken on line 6—6 of Fig. 1.

Like reference letters designate like parts in all the drawings.

In its more specific applicability this construction pertains to locking means for purses or ladies' pocket-books such as made in the form of a pair of book covers with an overhanging flap secured to one of the covers overlyingly and lockingly to engage the other cover, the locking member being carried by the flap of such purse or pocket-book and the coöperating or keeper member being secured upon the outer or front cover thereof.

In the drawings 1 represents the material of the flap of a purse to which is secured a box-like metallic plate 2 having side walls or flanges 3 at its outer edges and prongs 4 which pass through the material 1 of the flap, such as leather, textile material, leatherette, etc. Centrally through this plate 2 a perforation 5 is provided through which a stem or key 6 is adapted to be passed, said stem having at its outer end an appropriate knob 7 for manual manipulation. This stem 6, a short distance from its attachment to the inner face of the knob 7

is formed with a squared intermediate portion 8, while its remaining, rounded end portion is formed with two oppositely located transverse projections or lock lugs 9 whose function is to be hereinafter described. The perforation in the plate 2 is of extended or elongated form as shown at 10, (see Figs. 3—6) the elongations permitting the passage through the plate 2 of the projections 9 of the stem when in line therewith. A plate 11 is provided for the purpose of clamping the box-like plate and appurtenant parts securely to the flap 1, said plate having a perforation similar to the elongated perforation 10 and having, further, a plurality of perforations 12 near its edges which are located in line with the prongs 4 of plate 2 and engaged thereby by bending said prongs over the outer face of said plate 11 after they have been passed through the material 1 of the flap. In this manner the fastening member is secured to the flap 1, being clamped between the flanges 3 of the plate 2 and the inner face of the plate 11. The box-like flanged plate 2 supports and its flanges engage two, preferably U shaped leaf springs 13 and 14, oppositely located within the box, (as shown in Fig. 6) the arms 13^a and 14^a of said springs tending to exert pressure toward one another and against the flat, squared intermediate portion 8 of the stem 6 thereby resiliently maintaining the same against a turning or revolving movement.

I have thus far described the mechanism provided for the flap and shall now describe the coöperating members provided on the cover of the purse with which the flap is to be lockingly engaged. This member comprises a plate 15 secured upon the outer side of the cover 16 of the purse, said plate having a perforation 17 similar to the elongated perforation of plate 2, the said perforations in plates 2 and 15 in operative position being in transverse alignment with one another. This plate 15 is provided at its corners with a plurality of prongs 18 which, having been passed through the material of the cover panel 16 engage an inside plate 19 by being turned upon the inner face thereof, as shown at 19^a. This inside plate 19 as shown, may be made of rectangular form, the corners 19^b being slightly cut out to receive the prongs 18, which at the same time serve to retain the plate against displacement. If desired, however, said plate 19 may be pro-

vided with perforations similar to perforations 12 in which case, the prongs 18 would be passed through the material and the perforations 12 and bent over upon the inner 5 face of the plate 15.

The stem 6 is preferably soldered centrally to the inside face of the knob 7 and to avoid any unnecessary play between the knob 7 and the box-like plate 2, a coiled 10 spring 20 may be placed about the stem 6, braced against the inside face of the knob 7 and against the outer face of the box-like plate 2, the knob being preferably cup shaped, although if desired the same may 15 be made in the form of a solid block.

It will be noted from the foregoing description that when the parts described are assembled and the two members in operative relation the stem 6 will have been 20 passed through the perforation 5, the material 1, the inner plate 11, the plate 15 and the material 16 of the cover panel, the lock lugs in assembling being in alinement with the elongations of the perforations in the 25 plates 2, 11 and 15. To secure the flap to the cover panel of the pocket-book the knob is given a turn at right angles whereby the lugs 9 are turned into engagement with and overlap the rearward face of the plate 15 on the cover panel so that the two coöperating locking members will be in locking engagement. The pressure of the pair of U 30 springs against the squared portion 8 of the stem 6 resiliently maintains the stem and its lock lugs 9 in such locking position until by a positive return quarter-turn the lugs 9 will again be brought into alinement with the elongation of the perforation in plate 15 permitting the locking members to be 35 separated. For the purpose of limiting the movement of the stem in either direction to a one-quarter turn stops 21 may be provided on the rearward face of the plate 15 which stops are engaged by the lugs 9 in 40

moving them to either locking or unlocking 45 position.

What I claim and desire to secure by Letters Patent is:

1. A locking mechanism for a purse formed of relatively limber material, comprising a plate secured to the overlapping flap thereof said plate having a central perforation therethrough; a companion plate adapted to clamp the material of said flap in coöperation with said flap-plate and having a central perforation therethrough; a plate secured to the cover panel of the purse, said last mentioned plate having an elongated central perforation therethrough; a companion plate for said panel plate adapted to clamp the material of said panel in coöperation with said panel plate; a revolute stem passing through the perforations of the three plates first mentioned, said stem having intermediate its ends flattened surfaces; a leaf spring adapted to engage said surfaces and locking lugs at one end of said stem adapted to be engaged by and to be disengageable from the panel plate according to the turn imparted to said stem. 70

2. A locking mechanism for a purse comprising a plate secured to the flap, said plate having a perforation therein, a second plate secured to the outer cover, said latter plate having an elongated perforation therein, a revolute stem passing through the perforations of said plates said stem having along its length flattened surfaces, a coiled spring about said stem, a leaf spring on either side of a pair of said 80 flattened surfaces adapted to engage said pair of flattened surfaces, and locking lugs near one end of said stem adapted to be engaged by and to be disengageable from said latter plate according to the turn im- 85 parted to said stem.

CHAS. BAIA.
